United States Patent Office

Des. 198,837
Patented Aug. 11, 1964

198,837

SERVICE STATION

Donald A. Wexler, Palm Springs, Bernard Perlin, Los Angeles, George E. Boggio, La Habra, and Ernest E. Molina, Monterey Park, Calif., assignors to Union Oil Company of California, Los Angeles, Calif., a corporation of California

Filed Jan. 6, 1964, Ser. No. 78,089

Term of patent 14 years

(Cl. D13—1)

FIG. 1.

Des. 198,837

PAGE 2

FIG. 3.

FIG. 2.

FIGURE 1 is a plan view showing the juxtaposition of the building and associated canopy comprising the service station of our invention;

FIGURE 2 is a front elevation view of the aforesaid building and associated canopy;

FIGURE 3 is an elevation view of one side of said building and associated canopy;

FIGURE 4 is a rear elevation view of said building, said associated canopy being obscured by said building, and

FIGURE 5 is an elevation view of the opposite side of said building and associated canopy.

The dominant features of the design reside in the portions shown in full lines in the drawing.

We claim:

The ornamental design for service station, as shown and described.
